UNITED STATES PATENT OFFICE.

FRITZ KRAMER, OF BLANKENESE-DOCKENHUDEN, NEAR HAMBURG, GERMANY.

APPARATUS FOR MAINTAINING PRESSURE IN FUEL-OIL TANKS OF SUBMARINES.

1,412,357.

Specification of Letters Patent. Patented Apr. 11, 1922.

Application filed August 31, 1921. Serial No. 497,283.

(GRANTED UNDER THE PROVISIONS OF THE ACT OF MARCH 3, 1921, 41 STAT. L., 1313.)

To all whom it may concern:

Be it known that I, FRITZ KRAMER, a citizen of the Republic of Germany, and a resident of Blankenese-Dockenhuden, near 5 Hamburg, Germany, have invented certain new and useful Improvements in Apparatus for Maintaining Pressure in Fuel-Oil Tanks of Submarines, (for which I have filed application in Germany Aug. 2, 1918, issued 10 Sept. 22, 1920, Patent No. 326,026,) of which the following is a specification.

The fuel-oil containers of submarines are commonly disposed outside of the main hull and with walls which are not designed to 15 sustain any very great pressure difference on opposite sides. It is difficult to build and maintain such wall absolutely tight but leakage of oil from the tank is objectionable because it serves to indicate the location 20 of the submarine when submerged, and because of oil cost.

This invention is an apparatus by means of which a sub-pressure can be built up and maintained in the fuel-oil containers for the 25 purpose of preventing outward leakage of the fuel-oil.

Bearing the resisting strength of the tanks in mind, it is necessary to make such provision as will assure that, on the submersion 30 of the boat, the pressure caused by the seal on the outside of the tank wall will nearly if not quite be reached by the pressure on the interior of the tank wall.

In order to make sure that when the boat 35 is submerged, no oil will pass out through the tank walls, which in present existing constructions leak to a limited degree, it is important to keep, at all times, the pressure within the tanks not above that on the outside. The problem consists of maintaining 40 as nearly as possible, for every position and movement of the boat under water a certain counter-pressure in the tanks equal to or slightly below the pressure exerted by the 45 surrounding sea.

The desired sub-pressure in the fuel-oil tanks during submersion may be taken care of to a certain degree by the pressure difference caused by the friction of the flow 50 of the sea-water through the system of sea-piping, but this sea-piping is made large to take care of the rapid change in pressure resulting from quick submersion and

therefore offers very little friction and causes very little pressure difference. 55

The resistance of the piping-system can be easily increased in and made adjustable as for instance by the installation of a weighted valve. If the usual resistance of the pipe system is low compared to that of the valve then the valve will maintain a certain difference of pressure between the sea and the container, as long as the flow takes place from the sea toward the tank as in diving, but on rising the friction of the piping systems operates in the reverse sense as the flow now occurs from the tank to the sea, and it tends to produce a small over-pressure in the tank. 65

A sub-pressure when the boat is rising, 70 may be secured by the use of a pump, and the load imposed on the pump is determined by the speed of the rising.

By means of this invention it is possible to satisfy the various needs above referred 75 to, by an apparatus of the greatest simplicity possible, with lightness of weight, small space requirement, and smallest power consumption.

The invention in its preferred form consists of an arrangement whereby as soon as the boat is under water, a very small leakage pump is run to continuously draw from the tank and feed towards the sea, so that by the operation of this pump a flow line 80 between the tank and the sea is established. Two valves are so installed in by-passes around the pump that when a flow occurs from the seal towards the storage-tank a constant sub-pressure is maintained in the 85 tank for all pressures of the sea, and when the reverse happens and a flow exceeding the capacity of the pump occurs from the storage tank to the sea the smallest possible overpressure is produced. 90

The accompanying drawing shows one form which may be employed for the invention, the view being a sectional one. 95

1 is a valve chamber with a connection 2 with the sea and a connection 3 with the fuel-oil tank. The chambers 2 and 3 are separated from each other by two valves 4 and 5 and connected to each other by passages 6 and 9 between which the pump 7 is located. The space 2 connects with 100 the sea and the space 3 connects with the 105

portion of the oil-tank in which the inleaking sea water separates from the oil and collects by the difference in gravity of the two.

5 The pump which may be a gear pump or a centrifugal one, is driven by motor 8 and draws from space 3 and discharges into space 2. Valve 5 opens toward the tank and is loaded by a spring or in any suitable 10 manner as for instance, with such weight as to insure its acting only when a predetermined excess of pressure occurs in space 2 over that in space 3. The loading is such that the throttling down of the water passing into the tank produces the desired sub-pressure in the tank.

Independent of the valve 5 is a return-flow valve 4 which is made as light as possible and so disposed that an over-pressure 20 from space 2 towards space 3 will seat it and keep it closed but that the slightest over-pressure from space 3 towards space 2 will open it. The areas of spaces 2 and 3 as well as those of valves 4 and 5 are 25 of generous dimensions so as to permit rapid flow in case of need. On the contrary the passages 6 and 9 as well as the capacity of the pump are only for a very limited water flow, that is such as is considered the normal leakage of the storage tanks.

30 The operation is as follows: As soon as the boat dives the pump is started and runs continuously. It now pumps out to the sea such water as may normally pass due to 35 leakage of the tank walls and thus maintains in the fuel-oil tanks the desired sub-pressure. This sub-pressure corresponds to the loading of valve 5 which opens and allows the return of a part of the water fed by 40 the pump when the latter creates too great a sub-pressure.

If the boat goes still deeper then the pressure in space 2 increases and lifts valve 5 further allowing more water to flow from 45 the sea to the tank. Thus valve 5 continues to maintain the desired constant difference of pressure.

When the boat rises the pressure in space 2 falls. Valve 5 closes and valve 4 remains 50 closed as long as the pump can maintain a sub-pressure by delivering water from the tank towards the sea. When this is not possible, for example when the boat rises so rapidly that the compressible gases in 55 the tank can not expand quickly enough, then the valve 4 opens and prevents any super-pressure in the tank.

The particular advantages of the described arrangement are that the pump and motor

can be of small dimension and that their 60 load is small, furthermore that under all normal circumstances a certain sub-pressure is maintained in the fuel-oil tanks while under unusual circumstances no noteworthy super-pressure can develop.

Having thus described the invention what I claim is:

1. An apparatus for maintaining a sub-pressure in the fuel-oil tanks of submarine boats including a weighted inwardly opening valve, a non-loaded outwardly opening valve and an outwardly delivering pump operable independent of each other, whereby upon decreasing tank pressure a flow from the sea towards the tank occurs by the 75 weighted valve, and upon rising tank pressure, a flow is started from the tank towards the sea through pump and by a still greater increase of tank pressure the outflow occurs also through the second mentioned valve. 80

2. An apparatus for controlling the pressure of outboard oil tanks of submarines and preventing the leakage of oil therefrom including a pump of small capacity and acting to draw inleaking water from the 85 tank and normally maintaining a pressure in the tank below that of the surrounding sea and means for establishing communication between the tank and the sea independently of the pump in case of slight super-pressure or more than a predetermined sub-pressure in the tank. 90

3. An apparatus for controlling the pressure of outboard oil tanks of submarines and preventing the leakage of oil therefrom including a pump of small capacity and acting to draw inleaking water from the tank and normally maintaining a pressure in the tank below that of the surrounding sea, valve 95 mechanism opening upon slight super-pressure or more than a predetermined sub-pressure in the tank and permitting flow independently of the action of the pump. 100

4. An apparatus for controlling the pressure of outboard oil tanks of submarines 105 and preventing the leakage of oil therefrom including a pump of small capacity and acting to draw inleaking water from the tank and normally maintaining a pressure in the tank below that of the surrounding sea, and by-passes around the pump, one including a non-loaded outwardly opening valve and the other a loaded inwardly opening valve. 110

Signed at Hamburg, Germany, this 6th 115 day of August, A. D. 1921.

FRITZ KRAMER.
